UNITED STATES PATENT OFFICE.

LOUIS R. HORTON, OF PROVIDENCE, RHODE ISLAND.

DESIGN FOR A SPOON.

SPECIFICATION forming part of Design No. 24,939, dated December 3, 1895.

Application filed October 9, 1895. Serial No. 565,194. Term of patent 7 years.

To all whom it may concern:

Be it known that I, LOUIS R. HORTON, a citizen of the United States, residing at Providence, in the county of Providence and State 5 of Rhode Island, have invented and produced a new and original Design for Handles for Spoons and Similar Articles, of which the following is a specification, reference being had to the accompanying drawings, forming part thereof.

Figure 1 is a front view of the handle, shown in connection with the bowl of a spoon in solid lines, a fork being indicated in broken lines. Fig. 2 is a view of the reverse of the handle, 5 shown connected with the bowl of a spoon.

The leading features of my design consist in the shape of the handle, having distinct marginal raised edges, two lines of beading, the raised convex oval surmounted by an oval 5 ring of beads placed in the foliated ornament at the upper end of the handle, and in the oblong convex pear-shaped figure surrounded by a foliated ornament at the junction of the handle with the bowl at the reverse side of 5 the article.

The handle is formed by contracting the width of the bowl of the spoon or the fork into a narrow stem at 3. This stem enlarges very gradually toward both sides until it reaches the point 4, where it broadens out on a curved line until at the point 5 the outline is curved and continues nearly of uniform width to the point 6, from which point it curves outward and then inward, ending in 5 the foliated scrolls 7 at the upper end of the handle. The outer edge is rounded into the bead 8. Next to this bead is a line of beads 9

of gradually increasing diameter, the smaller being at the lower and the larger at the upper end of the front of the handle. The space 40 between the two lines of beads 9 forms a convex field or panel. The ornament at the upper end of the handle is placed between the foliated scrolls 7 7 and extends above and below the same. The central convex oval 11 45 is surrounded by the oval ring of semispherical beads, and from one of the foliated scrolls 7 to the other extends the diadem-shaped ornament which forms the extreme upper end of the handle. Below the central oval 11 a foliated 50 ornamentation resembling three-pointed cactus-leaves fills in the space between the foliated scrolls. On the reverse a raised bead follows the general outline of the handle, finishing at the upper end in two scrolls 14, between which the diadem-shaped ornament 13 forms the end of the handle. At the lower 55 end of the reverse of the handle a fan-shaped ornament extends over the enlarging portion of the handle where it unites with the bowl. 60 Below this the oblong pearl-shaped ornament 16 rises above the foliations 17, which at their base extend laterally and have the spirally-twisted ornament 18, extending centrally below the pear-shaped ornament 16. 65

What I claim is—

The design for a handle for a spoon or similar article herein shown and described.

In witness whereof I have hereunto set my hand.

LOUIS R. HORTON.
